KENYON COX AND THEODORE COX, OF NEW YORK, N. Y.

Letters Patent No. 109,390, dated November 22, 1870.

IMPROVEMENT IN WATER-WHEELS.

The Schedule referred to in these Letters Patent and making part of the same.

To all whom it may concern:

Be it known that we, KENYON COX and THEODORE COX, of the city of New York, in the county and State of New York, have invented new and useful Improvements in Water-Wheels; and we do hereby declare that the following is a full, clear, and exact description thereof, which will enable others skilled in the art to make and use the same, reference being had to the accompanying drawing forming part of this specification.

This invention relates to improvements in water-wheels of that class in which the hydrostatic pressure of the water is obtained by passing it through a circular case, in which the buckets or pistons fit closely between the induction and exhaust-ports on one side, and a cut-off device is used on the other side to prevent the back action of the water, and which are applicable for use as water-meters, rotary steam-engines, pumps, or blowers.

The invention consists in the combination, with radial buckets or pistons rigidly attached to the hub of the driving-shaft, of a drum or ring made in sections of rings, (preferably as many as there are pistons or buckets,) and fitted in grooves or guides at the ends of the case, eccentric to the piston-hub, which sections lap each other at the ends, and each has a hole at or about the center, through which a bucket extends, the whole revolving with the buckets and shifting on each other at thelapping ends, as required by the constant changes of the buckets, into the rim, due to the eccentric arrangement of the one to the other, and closing the space at one side of the wheel against the passage of the water.

Figure 1 is a transverse section of our improved wheel;

Figure 2 is a section perpendicular to the axis of the same; and

Figure 3 is a similar section, divested of the rim of the case, and showing a modification of the construction of the sectional ring.

Similar letters of reference indicate corresponding parts.

A is a circular case, having a longitudinal induction-chute, B, at one side of the axis, and a discharge-opening, C, at the other or thereabout, as may be preferred.

D is the shaft arranged in the axis of the case, and carrying the radial pistons or buckets E, projecting from a solid hub attached to it, and fitting the ends and rim of the case closely between the supply and discharge-ports.

H is a ring of metal, made in as many sections K as there are buckets, of which there may be two or more, wider than the space between the ends of the case, and fitted in a groove, I, in each, which grooves are arranged eccentric to the axis of the case, and so that they extend to the inner wall of the rim of the case, between chute B and discharge C, on the

side where the water is to be prevented from passing, as shown at J.

Each section of this ring has a hole at or about the center, through which one of the buckets projects, and they lap between the buckets so as to slide on each other, as the distances between the holes vary in consequence of the sections being moved out and in on the buckets by the eccentric grooves, around which the ring is carried by the buckets.

The said sections are adjusted, as to length, so that the ends will lap sufficiently to accomplish the object for which they are intended, when most extended, as indicated at L, where they are at the greatest distance from the axis of the wheel, and yet not lap so much on the opposite side as to interfere with the buckets, if arranged as in fig. 1, or with the shoulders M of each other, if arranged as represented in fig. 2, either of which arrangements we propose to make use of, or any other which will accomplish the same purpose.

The difference in the arrangements here shown consists in making the section in one case half on a greater and the other half on a lesser radius, so that one-half laps the half of the next section on the outside, and the other half laps its fellow section on the inner side; and in the other case each alternate section is wholly formed on the greater radius, and the other on the lesser.

It is not material which of these arrangements are used, or others equally as useful may be employed.

The holes through the sections have oblique walls, forming narrow bearings against the sides of the pistons, to admit of the vibrations necessary, owing to the eccentric arrangement of the one with the other.

It is believed that this arrangement will work with much less friction than those wherein the pistons are made to slide in the hub, and the latter is arranged eccentrically to the case, while the buckets sustain the pressure of the water, or others of that character, for in this case, there being no objection to the space within the ring being filled with water, the pressure on the ring will be equal on both sides, and the friction, other than that of the pistons on the sides and rim of the case, will be limited to that of the rings turning in the grooves and the working of the pistons through the holes of the rings, which will manifestly be but little in either case.

Having thus described our invention, we claim as new and desire to secure by Letters Patent—

The combination, with the wheel-case and the buckets or pistons, of a sectional ring arranged eccentrically to the axis of said case and buckets, substantially as specified.

KENYON COX.
